ELECTRIC HEATER

Anthony F. Copersito and Frank J. Copersito,
Brooklyn, N. Y.

Application April 5, 1946, Serial No. 659,920

2 Claims. (Cl. 218—\$4)

1

This invention has for its principal object the production of an electric heater or analogous device the parts of which may be easily assembled and disassembled whereby they may be packed into a compact package of small dimensions making for convenience in and lessening the cost of shipping.

A further object of the invention is the production of a device of the above character in which some of the parts shall be substantial duplicates of others thereby minimizing the cost of construction and facilitating the packing thereof.

A further object of the invention is the production of a device of the character described in which most of the parts shall be constructed of thin sheet metal as of tin, stainless steel and the like and having highly polished surfaces for reflecting heat or light rays, as the case may be, as well as to enhance the ornamental appearance of the device as a whole.

Other advantages of the invention consist in the provision of a cooling chamber forming a unitary part of the device for cooling a part of the necessary electrical apparatus and the provision of simple means whereby the parts making up the heat or light deflecting means may be easily and detachably held together, it being understood that the apparatus may be employed effectively with a sun ray or light ray tube or bulb.

Other and further objects and advantages of the invention will appear from the subjoined description, the invention consisting in the novel heater or analogous device hereinafter more particularly described and then specified in the claims.

In the accompanying drawing illustrating a practical embodiment of the invention:

Fig. 1 is a front elevation (partly broken away) of the device of the invention.

Fig. 2 is a vertical section on the line 2—2 of Fig. 1.

Fig. 3 is a horizontal section on the line 3—3 of Fig. 1 and,

Fig. 4 is a horizontal section on the line 4—4 of Fig. 1.

Referring in detail to the several figures of the drawing:

The numeral 10 indicates a supporting or body plate of sheet metal provided with an opening therein positioned preferably centrally thereof which receives an electrical fitting 11 supported within the opening in any manner and having a flexible conducting wire 12 connected therewith and adapted to be connected to a source of current supply. Said fitting carries a socket 13 re-

ceiving a two-way plug receptacle 14. Detachably screwed within the sockets of said receptacle 14 are the oppositely disposed cores or plugs 15 each carrying a heating coil 16 wound therearound and adapted, in the preferred form of the invention, to generate heat of considerable intensity when electric current is passed therethrough. In operation, one or both of said cores or plugs may be employed and they are easily and quickly replaceable when necessity arises.

The ends of the aforesaid supporting plate 10 are bent forwardly and at right angles thereto to provide substantially parallel locking flanges 18 and the longitudinal edges of said plate are bent over on themselves, first rearwardly, then forwardly, then rearwardly as indicated generally at 17 to provide longitudinal grooves 19 of substantial depth and strength.

The upper and lower inclined walls of the device of the invention and providing portions of the heat or light reflecting means are indicated at 19 and 20 respectively and said upper wall 19 may have a handle 21 of any desired construction bolted or otherwise secured to said upper wall. 21 These walls are also made of sheet metal and their inner surfaces at least are highly polished or provided with a finish having the same effect so that they will reflect outwardly either heat or light waves. In the embodiment of the invention shown said walls will reflect the heated air or heated air waves brought about by heat generated by the aforesaid heating coils 15. One longitudinal edge of each of said walls is bent over inwardly approximately at an angle of 45 degrees to the general plane of the wall to provide a longitudinal flange 22. These flanges are received within the grooves 19 of the supporting plate and are tightly and frictionally held therein. The opposite longitudinal edge of each of said walls is bent slightly over on itself to eliminate sharpness and is then bent at a considerable angle to the general plane of the wall to provide an elongated longitudinal hook or catch member 23. The ends of said walls also are bent over on themselves, 23 first inwardly and then outwardly as indicated generally at 24 to form grooves 25. When properly assembled, the walls 19 and 20 assume the outwardly flaring position shown in Fig. 2 so that the heated air will be reflected outwardly by said walls over a large area.

The side walls of the device are indicated at 26 and form with the body or supporting plate 10 and the upper and lower inclined walls 19 and 20 a heat-reflecting or light-reflecting open housing. Said side walls 26 comprise sheet metal

plates having polished inner surfaces and a configuration substantially that of an isosceles triangle the intersections of the shorter legs of which have been cut off. The shorter sides of said side walls are turned over at their edges to form right-angled flanges 27 which are received snugly and frictionally held within the grooves 25 at the ends of the inclined outwardly flaring walls 19 and 20. The longer and exposed edge of each of said side walls is bent over on itself as indicated at 28 to eliminate sharpness.

A rear plate spaced from and parallel to the supporting plate 10 is indicated at 29. It is provided with upper and lower forwardly extending right-angled flanges 30 engaging beneath and interfitting with the flanges 17 of the supporting plate 10. The rear plate is also provided with end flanges 31 extending forwardly intermediate the locking flanges 16 and the side walls or plates 26 hereinbefore described. Said rear wall or plate 29 is provided with an opening, as shown, for receiving the fitting 11 and also with a series of louvres or ventilating openings 32. The supporting plate with its rearwardly extending flanges and the rear plate with its forwardly extending flanges produce a cooling chamber for the fitting 11 which is apt to become electrically heated to a high degree when the device is in operation. A sheet of asbestos or other heat-resistant material 33 may be provided and which closely engages the rear side of the supporting plate 10 within the cooling chamber and has the function of preventing heat generated by the coils 15 and absorbed by the supporting plate from being radiated rearwardly.

For detachably locking and preventing disconnection of the parts which are held together frictionally, bolts 34 carrying winged nuts 35 are provided. Said bolts extend through the vertical arms of a bracket 36 and through the side walls 26, end flanges 31 and locking flanges 16 previously described. The bolts 34 may also carry compression springs 37 which bear against the arms of the bracket and against the side walls or plates 26 for imparting rigidity to the locking or clamping mechanism and to assist in holding the device in the desired adjusted position.

The bracket 36 may be detachably bolted or otherwise fastened to a stand or support 38 of any suitable material by the bolt and nut connection 39. Detachable and protective grilles or screens 40 are also provided and the upper and lower ends of which engage behind the hook or catch members 23 of the upper and lower inclined walls 19 and 20. Preferably none of the parts described exceeds in length or width the length or width of the stand or support 38 so that for convenience of shipping they all may be stacked or piled thereon with facility. Obviously, also, instead of being used as a heater, the device may be conveniently employed as a sun-ray lamp or a conventional illuminating or fluorescent lamp by substituting the proper bulbs or tubes for the cores 14 and heating coils 15.

The stand 38 also may be attached to any convenient member as the wall or ceiling of a room.

The invention claimed is:

1. In a device of the character described, a sheet metal support having opposed edges turned over on themselves to form grooves, flanges extending forwardly from said support, an electrically energizable device carried by said support, sheet metal upper and lower inclined walls each flanged at one of the longitudinal edges thereof, said flanges entering and frictionally held within said grooves and the ends of said inclined walls being turned over on themselves to form grooves, sheet metal side walls provided with flanges entering and frictionally held within the grooves in said inclined walls and locking means extending through said side walls and the forwardly extending flanges of said support for preventing relative movement of the aforesaid parts frictionally held together.
2. In a device of the character described, a support, an electrical fitting carried thereby, an electrically energizable device connected to said fitting, forwardly extending flanges on said support, a box-like structure engaging said support and receiving said fitting and having ventilating openings in a wall thereof, said box-like structure and support providing a cooling chamber for said fitting, locking flanges on said box-like structure, upper and lower walls flaring outwardly from said support and provided with edge portions detachably and frictionally held to cooperating elements on said support, side walls having edge portions detachably and frictionally held to cooperating elements on said upper and lower walls, said support, upper and lower walls and side walls together forming a knock-down reflecting enclosure housing said energizable device and open only forwardly of said energizable device and locking means extending through said side walls, forwardly extending flanges and locking flanges for preventing disconnection of said upper and lower walls from said support, said side walls from said upper and lower walls and for holding said box-like structure in engagement with said support.
